UNITED STATES PATENT OFFICE.

JOHN JEROME CASE, OF FORT EDWARD, NEW YORK.

PULP-GRINDING STONE.

1,091,037.

Specification of Letters Patent. Patented Mar. 24, 1914.

Application filed September 8, 1913. Serial No. 788,777.

To all whom it may concern:

Be it known that I, JOHN J. CASE, a citizen of the United States, and a resident of Fort Edward, in the county of Washington, 5 State of New York, have invented certain new and useful Improvements in Pulp-Grinding Stones, of which the following is a full and clear specification, reference being had to the accompanying drawings, in 10 which—

Figure 1 is a side elevation, partly broken away; and Fig. 2 is a vertical sectional view of a structure embodying the preferred manner of carrying out my invention.

15 This invention has relation to that class of pulp grinding stones in which the stone is of an artificial nature, molded to form while the material is in a plastic state, and the object of this invention is to provide simple 20 and efficient means whereby the stone may be readily and rigidly, as well as accurately, attached to the grinder shaft, these means permitting the stone to be readily detached from the shaft and replaced by a new stone 25 when the stone has become worn down below working size, as more fully hereinafter set forth.

Referring to the drawings by reference characters, *a* designates the usual shaft of 30 the grinder and *b* designates a cylindrical hub fastened to the shaft by a key *c*. At one end of the hub is formed an annular abutment flange *d* and at a point adjacent to this flange the annular surface of the hub is beveled at *e*, this bevel serving to give to this 35 part of the hub a conical shape, the base of the cone being at the juncture of the hub and the flange *d*. At the opposite end of the hub it is provided with an annular beveled 40 surface *f*, the direction of this bevel being inward toward the end of the hub.

Upon the above described hub, the grinding stone is adapted to be fitted. In the present instance, this stone consists of a 45 sleeve or metal ring *g*, which is approximately the length of the hub and at its ends is provided with annular flanges *h*, these flanges forming a sort of annular channel for the reception and retention of the artificial stone material *i* which is molded into the channel while in a plastic state. For the purpose of strengthening and reinforcing the stone, I provide the sleeve *g*, about midway its length, with an additional annular flange *j* and with small rods *k*, these rods *k* being mounted in the flange *j* and lying ap-

proximately parallel with the axis of the sleeve or ring *g*. I prefer also employing annular reinforcing wires or rods *l*. The stone as thus constructed and mounted is 60 adapted to be slipped on to the hub and at one end of the sleeve *g* said sleeve is beveled off on its inner face to correspond with and fit against the beveled annular surface *e* of the hub. When thus slipped over the hub, 65 one end of the ring or sleeve *g* abuts against hub flange *d*, and, to force the stone inwardly upon the hub to bring the surfaces of the ring or sleeve *g* into rigid abutting relation to the said flange *d* and conical enlargement *e*, I employ a clamping ring *m* which is removably secured to the opposite end of the hub by means of bolts *n* and which overlaps upon the adjacent face of the flanges *h* of the ring or sleeve *g*, so that by 70 tightening the bolts *n* the clamping ring *m* is drawn tightly against the face or end of the sleeve *g* and thus jams said ring or sleeve inwardly against the flange *d* and the conical surface *e*. For convenience in applying 75 and in removing the clamp ring *m*, it is preferably constructed in two semi-circular sections, and, in order that the stone shall be locked against rotative movement of the hub, I provide the end faces of the ring *g* 80 with bosses or lugs *o* and provide the flange *d* and the clamp ring *m* with marginal recesses for the reception of said bosses or lugs. To provide for accurate centering of the 85 stone when it is clamped in place, I provide the clamp ring *m*, on its inner face, with a wedge-shaped inwardly projecting annular flange *p* which, when the clamp ring is bolted home, will be forced inwardly between the beveled annular face *f* formed on 90 the adjacent end of the hub and an oppositely beveled face formed on the interior of the adjacent end of the stone-carrying sleeve *g*. It will be seen that when the clamp ring is drawn up by means of the abutment *n*, 95 the beveled surfaces will not only cause radial tightening action, but will also insure the perfect centering of the stone on the grinder shaft.

A feature of great importance is that with 105 my construction the stone and its carrying ring or sleeve as well as the reinforcements perform a unitary structure which is adapted to be placed on the shaft and removed therefrom as a unit, and which effectually 110 prevents all the strains of rigidly clamping the stone to the hub from being transmitted

to the stone-making material, thereby permitting the stone to be rigidly clamped in place without injuring it.

Having thus described my invention, 5 what I claim is—

1. In a pulp grinding device, the combination of a shaft, a hub thereon, a pulp stone structure embodying a metallic sleeve adapted to fit over said hub and carrying an artificial stone body molded thereon, and means for clamping, as well as centering, the pulp stone structure, said means serving to interlock said hub with said ring of the pulp stone structure.
- 10 2. In a pulp grinding device, the combina-

tion of a shaft, a cylindrical hub affixed thereto and having an annular beveled surface at each end, a metallic ring carrying a pulp stone and adapted to fit over said hub, said ring having an annular beveled surface 20 at each end of its interior surface, and a removable clamp ring having a wedge-shaped annular flange for the purpose set forth.

In testimony whereof I hereunto affix my signature in the presence of two witnesses. 25

JOHN JEROME CASE.
